EAVES TROUGH CLEANING DEVICE

Albert R. Froehlke, 742 33rd St.,
South Bend, Ind. 46615

Filed Dec. 29, 1971, Ser. No. 213,784

Term of patent 14 years

Int. Cl. D23—01

U.S. Cl. D23—34

FIG. 1 is a perspective view of an eaves trough cleaning device embodying my new design;

FIG. 2 is a fragmentary elevational view of the side of the eaves trough cleaning device shown in FIG. 1;

FIG. 3 is an elevational view of another side of the eaves trough cleaning device; and

FIG. 4 is an end view of the eaves trough cleaning device.

I claim:

The ornamental design for an eaves trough cleaning device, substantially as shown.
